UNITED STATES PATENT OFFICE.

MAXIME ALFRED LAUBEUF, OF PARIS, FRANCE.

SHELTER FOR USE IN CONNECTION WITH SUBMARINE VESSELS.

No. 921,125.

Specification of Letters Patent.

Patented May 11, 1909.

Application filed February 24, 1908. Serial No. 417,567.

To all whom it may concern:

Be it known that I, MAXIME ALFRED LAUBEUF, a citizen of the Republic of France, residing at Paris, in the Department of the 5 Seine, France, have invented certain new and useful Improvements in Shelters for Use in Connection with Submarine Vessels, of which the following is a specification.

My present invention pertains to submarine vessels, and relates more particularly to an improved shelter for the captain or helmsman (or both) when the vessel is being navigated upon the surface of the water.

The ordinary fixed shelter such as is now employed tends to impede the passage of the vessel (when submerged) through the water as well as being a source of danger by reason of its exposure and consequent liability to damage by collision.

20 The shelter forming the basis of the present case may be collapsed or folded down upon the deck of the vessel, in which position it will remain while the vessel is submerged, thus offering a minimum of resistance.

25 The invention is illustrated in the annexed drawings, in which:

Figure 1 is a perspective view of the shelter shown as erected and viewed from the front; Fig. 2 a vertical sectional view, taken on the 30 line 2—2 of Fig. 3; Fig. 3 a horizontal sectional view, taken on the line 3—3 of Fig. 2; Fig. 4 a transverse sectional view, taken on the line 4—4 of Fig. 2; Fig. 5 a detail vertical sectional view, taken on the line 5—5 of Fig. 35 1; Fig. 6 a similar view, taken on the line 6—6 of Fig. 4; and Fig. 7 a perspective view, partly broken away, showing the parts in their folded or collapsed position.

In a broad sense the shelter may be said to 40 comprise two sides which stand at approximately right angles to each other, with the edges abutting toward the bow of the vessel, and a cover resting upon the upper edges of the sides.

45 In the drawings, A denotes one side, B the opposite side, and C the cover, the upper edges of the sides being inclined downwardly toward the front edge thereof so that the cover slants forwardly and tends to prevent the passage of spray or water over the rear portion thereof. A plate D is secured above the deck by an angle-bar E and a similar plate D' is secured above the deck by an angle-bar E', the plates D and D' standing at 50 approximately right angles to each other, with the angle pointing toward the bow of

the vessel. These plates will preferably be arranged forward of the hatchway, which is denoted by F. Hinged to the plate D is the side A, while hinged to plate D' is the side B. 60 To the forward portion of the side A and standing in line with the front edge thereof is secured an angle plate G (see Fig. 4). A similar angle plate H is secured to the side B. These angle plates serve to stiffen the sides 65 and likewise to make a comparatively tight joint at the forward portion of the shelter.

A U-shaped angle-bar I is secured to one edge of the cover, the bar being notched out, as shown in Fig. 6, to permit one member 70 of the hinges J (which connect the top or cover C to the side A) to pass through the bar. A similar bar K is secured to the opposite edge of the cover. Said bar K is provided in its outer member with elongated 75 openings or slots L, and with smaller openings in the inner flange thereof.

The side B is provided at its upper edge with a stiffening plate M, and openings are formed through said plate and the side in 80 line with the slots and openings in the bar K. A rotary bolt N extends through the openings, and a tongue O, formed upon the outer end of the bolt, is passed through the elongated slots and turned down to the position 85 shown in the drawings after the sides A and B have been drawn upward and the cover C swung down into position. When the parts are thus in place the U-shaped bars I and K embrace the upper edges of the sides 90 A and B and the members are thus locked together.

If desired, suitable braces may be employed in conjunction with the sides A and B. Such braces are shown in Figs. 1, 2 and 95 3. Pivotally secured to the sides A and B are two-part hinged rods P, the lower ends of the rods being hinged to the deck. A sliding collar Q is preferably mounted upon each of the rods, and when the rods are in 100 their extended position the collars move over the hinge joints of the rods and prevent the same from being moved.

As an alternative construction, or one which may be used in conjunction with the rods P, I may employ brace rods R, hinged to the deck (as shown in Fig. 3) forward of the shelter and connected at their upper ends by eyes S to the sides A and B.

While the vessel is being navigated below 110 the surface of the water the parts will be in the positions shown in Fig. 7; that is to say,

the parts will be unlocked, the side B folded down upon the deck, the top C folded against the side A, and the top and side A then folded over and upon the side B. The shelter thus collapsed occupies only a small space and makes but a slight projection above the deck of the vessel.

It is possible that the sides A and B might be employed without the cover, but where 10 the cover is used, as it will be in most instances, windows T are provided in the side walls, in order that the captain or navigator may have the proper field of vision.

It is conceivable that in so far as the generic invention is concerned the details of the structure may be varied without departing from the spirit of the invention.

Having thus described my invention, what I claim is:

20 1. In combination with the hull of a submarine vessel, a pair of plates hinged thereto at substantially right angles to each other; and a cover extending across the top of said plates.

25 2. In combination with the hull of a submarine vessel, a pair of plates hinged thereto at substantially right angles to each other; and a cover hinged to the upper portion of one of said plates and adapted to be swung down into contact with the upper portion of the opposite plate.

30 3. In combination with the hull of a submarine vessel, a pair of plates hinged thereto at substantially right angles to each other, the adjacent edges of the plates coming into close relation with each other when the plates are swung upward into a substantially vertical position; and a cover hinged to the upper portion of one of said plates and adapted to contact with the upper portion of the opposite plate when the cover is swung into position.

35 4. In combination with the hull of a submarine vessel, a pair of plates hinged thereto, said plates standing at approximately right angles to each other, with the forward edges of the same coming into contact when the plates are placed in a vertical position; a cover hinged to the upper portion of one of said plates; and means for securing the cover to the opposite plate when the cover is brought to position.

40 5. In combination with the hull of a submarine vessel, a pair of plates hinged thereto at approximately right angles to each other,

the forward edges of the plates coming into substantial contact when the plates are brought to their normal vertical positions, the upper edges of said plates being inclined forward; and a cover hinged to one of said plates at the upper edge thereof and adapted to rest upon the upper edge of the opposite plate.

6. In combination with the hull of a submarine vessel, a pair of plates hinged thereto at approximately right angles to each other, the forward edges of the plates coming into substantial contact when they are swung into upright position; a cover hinged to one of said plates and adapted to rest upon the upper edge of the opposite plate when the cover is positioned; and brace rods connected to the deck and to the plates.

7. In combination with the hull of a submarine vessel, a pair of plates hinged thereto at substantially right angles to each other; an angle-bar secured to each plate adjacent the forward edge thereof and serving to stiffen the same; a cover hinged to the upper edge of one of said plates and adapted to rest upon the opposite plate; and means for securing said cover in position.

8. In combination with the hull of a submarine vessel, a pair of plates hinged thereto at substantially right angles to each other; a cover hinged to the upper portion of one of said plates; U-shaped members secured to the under face of the cover adjacent to its edges, said members being adapted and designed to receive the upper edges of the plates; and means for securing said cover in position.

9. In combination with the hull of a vessel; a pair of plates hinged thereto, the pivotal axes of the plates converging in a plane passing vertically through the longitudinal axis of the vessel, whereby when the plates are in their upright position they form a wedge-shaped shelter.

10. In combination with the hull of a vessel; a pair of plates hinged thereto at an angle to the longitudinal axis of the vessel, the plates converging toward their forward edges; and a cover.

In testimony whereof I have signed my name to this specification in the presence of two subscribing witnesses.

MAXIME ALFRED LAUBEUF.
